UNITED STATES PATENT OFFICE.

HARRY S. FOLGER, OF CHICAGO, ILLINOIS.

HAND-STAMP.

1,142,561.

Specification of Letters Patent. Patented June 8, 1915.

Application filed March 2, 1914. Serial No. 822,081.

To all whom it may concern:

Be it known that I, HARRY S. FOLGER, a citizen of the United States of America, and a resident of Chicago, county of Cook, and 5 State of Illinois, have invented certain new and useful Improvements in Hand-Stamps, of which the following is a specification.

My invention relates to hand stamps and has for its object improvements in devices of 10 that character.

In the accompanying drawings Figure 1 is a perspective view; Fig. 2 is a transverse section, partly in elevation; Fig. 3 is a modification of Fig. 1; Fig. 4 is a modification of 15 Fig. 3; and Fig. 5 is a section of line 5—5 of Fig. 4.

The stamp cushion 6, carrying type faces 7, is secured in a sheet metal box consisting of a top plate 5 having three edges or sides 4 20 turned downward to inclose three sides of the cushion 6. The fourth side 10 is somewhat longer than the other sides and is bent upward to form a card holder.

The top plate 5 and the sides 4 constitute 25 a stamp mount, and in the center of the plate 5 is secured a screw 8, and on this screw is a stamp handle 9. The upwardly projecting part 10 is made into a card holder by punching from opposite edges thereof 30 the teeth 11 to form a channel into which the card may be slipped. In Figs. 1 and 2 this channel is horizontal by reason of the teeth 11 being struck from the upper and lower edges of the part 10. In Fig. 3 the 35 channel is vertical by reason of the teeth 11 being struck from the opposite ends of the part 10. In this last case additional teeth are struck from the lower edges of the part 10 to hold the inserted card from slipping 40 downward in its channel.

In Fig. 4 the vertical card-holding channel is formed by bending the edges 12 into a groove for holding the edge of the card.

To prevent the card from slipping downward in the groove the lower edge is closed 45 by cutting the lip 12 and bending it inward as shown at 13. Into the card-holding channel formed in any of these ways may be slipped a card bearing an inscription indicating what the stamp is.

It will be observed that the stamp mount and the card holder are made complete out of a single piece of sheet metal, and that the construction is simple, cheap and efficient.

What I claim is:

1. In a hand stamp, a sheet metal plate having one portion bent at an angle to the other portion, one of said portions serving as a stamp mount and being provided with 60 means for the attachment of a handle, and the other of said portions having teeth punched therefrom and formed into a card holding channel located at the side of and above the stamp.

2. In a hand stamp, a metal plate having a horizontal portion serving as a stamp mount and a vertical portion serving as a card holder, the horizontal portion being provided with means for the attachment of 70 a handle and the vertical portion having parts thereof cut and bent from the remaining parts to form a card holding channel.

3. In a hand stamp, the combination with a stamp body and a handle, of a combined 75 stamp and card holder formed of a single plate having one edge bent to form the card holder and the other edges bent to form a stamp box.

Signed at Chicago, Illinois this 24th day 80 of February 1914.

HARRY S. FOLGER.
